COVERING MATERIAL

Samuel C. Straub, New York, N. Y., assignor to
 Certain-Teed Products Corporation, New York,
 N. Y., a corporation of Maryland

Application January 20, 1933, Serial No. 652,606

10 Claims. (Cl. 20—5)

This invention relates to covering for laying upon a surface and more especially upon the surface of walls to simulate a structure of masonry.

5 The invention relates more particularly to a covering sheet having its surface to be exposed so made as to simulate a plurality of courses of masonry and of a form for laying in complementary relation to other covering sheets upon 10 the surface.

Coverings having for their purpose the simulation of masonry structures heretofore have been proposed in various forms, including strips and sheets upon the surface of which the simulation 15 of the masonry joints has been applied, such as by printing contrasting stripes upon the sheet or by embossing grooves in a plastic covering upon the surface of the sheet. Simulations of brickwork construction have been attempted by using shingles or shingle strips in which a cutout or 20 notch has been used to simulate the vertical joint of the brickwork without particular means upon the strip for sharp demarcation of the horizontal joint of the brickwork. The method of printing is unsatisfactory owing to the lack of characteristic appearance of the joints, especially the vertical joints, and the method of embossing the 25 channels in the coating involves the use of expensive embossing rolls. In the constructions in which the simulation of the horizontal joint of brickwork has not been provided a characteristic 30 simulation of the brickwork construction also is not obtained. Moreover, when a plurality of courses of masonry is simulated upon the sheet 35 the problem of suitably forming the joints between adjacent sheets to make said joints inconspicuous has not been solved heretofore.

It is an object of the present invention to provide a covering sheet which may be easily formed 40 so as to simulate a plurality of courses of masonry and which will not require expensive machinery but may be manufactured with the ordinary machinery used for the production of covering materials such as roofing.

45 It is also an object of the invention to provide such a covering unit with a sharp demarcation of the longitudinal as well as the transverse joints of masonry, whether of brickwork or other type of construction, without the necessity of manufacturing the unit by expensive methods.

50 It is a further object of the invention so to form the covering sheets that they may be laid adjacent each other in complementary relation with 55 the joints between the sheets inconspicuous and

without marring the appearance of the masonry simulating areas.

Other objects of the invention will appear from the following description.

The invention provides a covering sheet upon 5 which are simulated the masonry units separated by longitudinal stripes of contrasting shade or color for the simulation of the longitudinal joints. Said stripes simulating the longitudinal joints are continuous longitudinally of the covering and 10 separate discontinuous longitudinally extending areas which provide the simulation of the masonry units. When simulating brickwork constructions, said discontinuous longitudinally extending areas substantially form discontinuous 15 horizontal and parallel vertically spaced stripes of similar shade and color, said discontinuous stripes being vertically spaced by the continuous stripes contrasting therewith and simulating the horizontal joints or mortar lines of the brick- 20 work construction.

In order to provide the discontinuous stripes according to my invention I form notches or cutouts through the material of the sheet, that is, the base upon which the simulation of the 25 masonry structure is made. These notches or cutouts extend transversely to the longitudinal continuous stripes and separate the simulated masonry units. In the simulation of a construction such as brickwork in which the vertical joints 30 of the brickwork are in staggered relation in successive courses of brick, said transverse notches or cutouts extend between longitudinal continuous stripes. Thus the areas simulating the 35 masonry units or the bricks are demarcated by the longitudinal continuous stripes and the transverse notches or cutouts.

While I may provide the simulation of the longitudinal stripe by any convenient method, including printing or embossing, I prefer to utilize the method described in the patent to Outman 1,426,497 in which in a coating applied upon a base sheet longitudinal grooves are scraped because said method avoids the objections mentioned above. By such means I am able to provide a sharply demarcated simulation of the longitudinal joints of the masonry by an inexpensive and convenient process. Moreover, when used in the simulation of masonry upon the surface of roofing materials, particularly roofing materials having a coating of asphalt upon a base sheet, upon which asphalt coating may be applied a mineral surfacing material, I am able to obtain the sharp demarcation while at the same time providing a character of surface upon said longi- 55

tudinal scraped stripe which serves to simulate the character of the masonry joint. This is especially true when the simulation of masonry set up in black mortar is desired, since the surface presented by the scraped asphalt is of such a character as suitably to simulate said mortar.

By using a cutout through the base sheet for the simulation of the transverse or vertical joints of the masonry, I secure a sharply demarcated outline for the masonry units and I am able, by the ordinary methods of cutting notches in covering materials such as are practiced in the roofing art, in a single operation or in consecutive operations without special handling, to form the simulation of the longitudinal joints and of the transverse joints as explained above. Such methods may be practiced by providing a cutting roll or other usual cutting device in cutting the sheet, as described in said patent to Outman, which roll will form the notches in proper relation to the stripes.

Thus I may produce a sheet which provides the simulation of a plurality of courses of masonry and the simulation of the joints of mortar in which the masonry units are laid. The simulation of the transverse joints of the masonry lying between masonry units which are adjacent the edges of the sheet may be provided by notches of suitable width extending from the edge of the sheet to meet the simulated longitudinal joints nearest to said edges. The simulated transverse joints between units lying in intermediate courses of the masonry may be provided by cutouts of suitable width between the simulated masonry units in the intermediate courses and extending between the simulated longitudinal joints adjacent said courses. By utilizing said notches and cutouts not only is a sharp demarcation of the transverse joint provided, but the transverse joint may be given the proper appearance by providing upon the surface which is to be seen through the cutout or notch a surfacing material of a characteristic which will simulate that of the mortar in masonry joints.

My invention also provides in a covering of the type above described a form of the sheets such that when laid upon the surface in complementary relation to each other the simulation of the masonry or of the brickwork may be carried out over the surface to be covered. In order to accomplish this purpose, I so form the edge of the sheet that said edge is cut substantially along the simulated joints of the masonry. Thus I am able to avoid cutting across the area of simulated masonry units and, moreover, by confining the cut edges of the sheet to the simulated joints, the joint between sheets laid upon the surface becomes inconspicuous whereas when the sheet is cut along a straight line or a line of considerable extent in any direction as in coverings heretofore proposed, particularly if said line crosses a simulated masonry unit, the joint between the sheets becomes difficult, if not impossible, to conceal and the proper simulation of the masonry structure is not obtained. The sheet made by cutting along the simulated masonry joints in most cases acquires an offset or a stepped form as may be seen in the drawing. The invention is illustrated in the drawing in the particular embodiment showing a brickwork construction.

In said drawing Figure 1 is a face view of the covering sheet;

Figure 2 shows a modified form of the invention in the complementary arrangement; and Figure 3 is a cross section on line 3-3 of Figure 1 or 2.

In Figure 1 is shown a sheet 1 having thereon continuous stripes 2 extending lengthwise of the sheet, said stripes being spaced apart and being spaced from the edges of the sheet distances suitable to simulate the spaced longitudinal joints of masonry. Between said continuous stripes 2 simulating the longitudinal joints are discontinuous stripes of contrasting color or shade providing the areas 3 for simulation of the bricks. Said areas 3 are separated by the transverse notches 4 or transverse cutouts 5.

As stated above, I may form the horizontal joints of the brickwork as shown in Figure 1 by scraping the stripes 2 in the asphalt coating upon a roofing sheet, the stripes 2 then having a surface character similar to black mortar. The areas 3 between said continuous stripes 2 may be coated with mineral surfacing material such as granular slate represented in Figure 3 by the numeral 6, the asphalt coating being there shown at 7. Thus, the surface of the areas 3 may be given a character similar to that of the surface of brick and contrasting with the stripes 2. The vertical joints of the brickwork are simulated by the notches 4 or the cutouts 5 and sharply demarcate the areas 3 and contrast therewith. Said contrast may be provided merely by the cutout by which is secured a shadow effect as well as the sharp demarcation provided by the cut material, or the surface upon which the covering of my invention is laid may be given a suitable character so that said surface may be seen through the cutouts and may simulate the mortar of said transverse joints.

In Figure 1 there is shown also the stepped form of the covering of my invention. It will be noted that the right hand edge of the sheet has been cut along the joints of the masonry, i. e., along both the vertical and the horizontal joints. It will be clear that such a form of stepped edge may be provided by cutting a continuous sheet in the lines 10 extending generally along the longitudinal joints 2 and connecting cutouts 4 or 5. In the particular form illustrated said lines 10 slope along the longitudinal stripe 2 between courses of the offset bricks. Thus, such a sheet may be severed into two parts, one having the form of Figure 1 and the other a form complementary thereto. Said stepped edges on the two sheets will be complementary and will fit together when laid upon a surface.

In Figure 2 is shown an assembly of two units of complementary shape having the end edges cut in staggered or offset form. From the figure it may be seen that said edges are cut along the simulated longitudinal joints 2 and connecting the staggered or offset vertical joints 4 and 5, thus similarly to the form shown in Figure 1 providing the feature of the invention by which the edges of the sheet are made without cuts across the area simulating the masonry joints, that is, they are made within the lines of the simulated masonry joints.

The forms of edges shown in Figures 1 and 2 are illustrative of the invention, but the invention is not limited to the particular forms there shown. The cuts along the longitudinal joints 2, without departing from the invention, may be made along other lines than along the sloping lines at 10 as shown in the figures. Within the scope of my invention, however, I provide the offset or stepped

form by cutting along any lines lying within the simulated longitudinal and vertical joints.

The invention is not limited to a particular kind of sheet material nor to particular methods of forming the horizontal stripes nor of cutting the transverse notches and cutouts. However, in my invention I use a continuous longitudinal stripe separating discontinuous stripes or areas of contrasting color, which discontinuous areas provide the simulation of the masonry units because of the separation obtained by the notches or cutouts. I further provide the stepped form of the edge of the covering by so cutting a sheet along the simulated longitudinal and transverse joints that complementary edges upon two sheets may be obtained for laying in complementary relation upon a surface to provide full coverage thereof without conspicuous joints between adjacent covering sheets and without waste of the material of the sheet except that removed in forming the cutouts.

What is claimed is:

1. A covering sheet for laying on a surface, comprising a base having at least a portion of the surface thereof demarcated into areas simulating masonry units laid in a plurality of courses with mortar joints therebetween, all the exposed edges of said sheet being formed by cuts through the base but without cuts across the areas simulating the masonry units to form all the edges at an end of the sheet which are transverse to said courses offset successively in one direction lengthwise of said courses.

2. A covering sheet for laying on a surface, comprising a base having at least the portion of the surface thereof to be exposed demarcated into areas simulating masonry units laid in a plurality of courses with mortar joints therebetween, the longitudinal joints of the masonry being simulated by at least one stripe upon the sheet and the simulated vertical joints being in offset arrangement, the ends of the sheet being of the offset form provided by cutting the base along lines of the simulated joints of the masonry and with cuts transverse to the courses successively offset in one longitudinal direction.

3. A covering sheet for laying on a surface, comprising a base having at least a part of the surface thereof demarcated by at least one stripe across the sheet and by cuts in the base extending transversely of the stripe into areas simulating masonry units laid in a plurality of courses with mortar joints therebetween in offset arrangement, the ends of said sheet transverse to said stripe being in the offset arrangement of the joints of the masonry as provided by cuts along the stripe each joining two transverse cuts, said ends having the transverse edges thereof offset in one direction lengthwise of said stripe.

4. A covering for laying upon a surface upon which is simulated a plurality of courses of masonry units, said simulated masonry units being provided by discontinuous longitudinal transversely spaced stripes having a surface character simulating the masonry units, said discontinuous stripes being separated by continuous longitudinal stripes having a surface of a character contrasting with that of said discontinuous stripes to simulate the longitudinal joints of masonry, said covering having cuts therein extending transversely of said continuous longitudinal stripes and dividing said discontinuous stripes into a series of areas simulating the masonry units, said cuts being so formed as to simulate the transverse joints of the masonry, said covering having the

edge thereof extending generally transversely of the longitudinal dimension of the covering cut longitudinally along the longitudinal joints and transversely along the transverse joints of the masonry with all transverse edges of the sheet offset successively in one longitudinal direction.

5. A covering sheet for laying upon a surface in complementary arrangement with similar covering sheets which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries at an end of the sheet completing an outline of said end having a stepped form with all said transverse boundaries successively offset in one longitudinal direction.

6. A covering sheet for laying upon a surface in complementary arrangement with similar covering sheets which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries at the ends of the sheet completing an outline at said ends having a stepped form rising at each end in the same direction and successively in one direction longitudinally of the sheet.

7. A covering sheet for laying upon a surface in complementary arrangement with similar covering sheets which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries at the ends of the sheet completing an outline of said end having a stepped form with said transverse boundaries successively offset in one longitudinal direction, the stepped form at one end being complementary to the stepped form at the other end while providing for the simulation of the vertical joints of the masonry at said ends of the sheet.

8. A covering sheet for laying upon a surface in complementary arrangement with similar covering sheets which comprises a base having upon at least a portion of the surface thereof a simulation of masonry units laid in a plurality of courses with mortar joints therebetween, the longitudinal boundaries of said portion of the surface extending along lines coincident with the simulated longitudinal joints of the masonry, the transverse boundaries at the ends of the sheet completing an outline of said end having a stepped form with said transverse boundaries successively offset in one longitudinal direction, the stepped form at one end being complementary to the stepped form at the other end while providing for the simulation of the vertical joints of the masonry at said ends of the sheet, the complementary edges of the sheet being parallel and equal except as modified by removal of a portion of the base to simulate the vertical joints at the ends of the masonry units simulated upon the sheet.

9. A covering sheet for laying upon a surface in complementary arrangement with similar covering sheets, which comprises a base having

upon at least a portion of the surface thereof a simulation of masonry units laid in a plurality of courses with mortar joints therebetween, the longitudinal boundaries of said portion of the surface extending along lines within the simulated longitudinal joints of the masonry, the transverse boundaries of said portion extending along lines within the simulated transverse joints of the masonry and completing an outline for said portion with the transverse boundaries offset successively in one longitudinal direction.

10. A covering sheet for laying upon a surface comprising a base having at least a portion of the surface thereof demarcated into areas simulating masonry units laid in a plurality of courses with mortar joints therebetween, said sheet at an end thereof being cut along the simulated transverse joints of the masonry and being cut along a simulated longitudinal joint connecting said transverse joints upon a line sloping across said longitudinal joint.
